(57) **CLAIM**

The ornamental design for a video borescope connector, as shown and described.

DESCRIPTION

FIG. 1 is an isometric view of a video borescope connector; FIG. 2 is a front view of the video borescope connector of FIG. 1;

FIG. 3 is a left view of the video borescope connector of FIG. 1;

FIG. 4 is a right view of the video borescope connector of FIG. 1; and,

FIG. 5 is a top view of the video borescope connector of FIG. 1.

The broken lines represent portions of the video borescope connector that form no part of the claimed design.

1 Claim, 5 Drawing Sheets
